CLAIM

The ornamental design for a pet drink bottle, as shown and described.

DESCRIPTION

FIG. 1 is a top perspective view of a pet drink bottle;

FIG. 2 is a rear view thereof;

FIG. 3 is a front view thereof;

FIG. 4 is a right side view thereof;

FIG. 5 is a left side view thereof;

FIG. 6 is a top view thereof;

FIG. 7 is a bottom view thereof; and,

FIG. 8 is a bottom perspective view thereof.

The broken lines depict exemplary graphics that form no part of the design claim but are shown for illustrative purposes.

1 Claim, 7 Drawing Sheets
